THERAPEUTIC APPLIANCE

William B. Rupe, Louisville, Ky.

Application December 11, 1944, Serial No. 567,599

8 Claims. (Cl. 128—79)

This invention relates to a therapeutic appliance and it is primarily an object of the invention to provide an appliance of this kind for use in connection with the penis to serve as a urinal check in cases of uncontrollable kidneys and which also may be used to impart rigidity to the organ and to maintain such rigidity to facilitate treatment of the organ.

It is also an object of the invention to provide an appliance of this kind which may be applied without injury and wherein the appliance embodies a cushioned structure for effective engagement when applied.

The invention consists in the details of construction and in the combination and arrangement of the several parts of my improved therapeutic appliance whereby certain important advantages are attained and the article rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein—

Figure 1 is a view partly in longitudinal section and partly in elevation of a therapeutic appliance constructed in accordance with an embodiment of the invention, an expanded position of the cap member being indicated by broken lines;

Figure 2 is a diagrammatic view illustrating the general assembly;

Figure 3 is a sectional view taken substantially on the line 3—3 of Figure 1; and

Figure 4 is an enlarged sectional view taken longitudinally through the meeting edges of the sleeves.

In the embodiment of the invention as illustrated in the accompanying drawing, C denotes a core member which is of rubber or kindred yieldable material. This member C is tubular and open at both ends with its wall 1 of material thickness. While the member C possesses a certain degree of inherent flexibility, it normally maintains a substantially cylindrical form.

The wall 1 of the member C is provided therealong with a series of openings 2 which are substantially equidistantly spaced and aligned in a plane substantially parallel to the axis of the member C. In the present embodiment of the invention, these openings 2 are of an unequal number and at opposite sides thereof are the series of openings 3 also aligned lengthwise of the

member C. These series of openings 3 are substantially equidistantly spaced from the openings 2 and the openings 3 of one series are substantially diametrically opposed to the openings 3 of the second series. Each series of openings 3 are of equal number and are staggered with respect to the openings 2. Corresponding openings 3 are substantially circumferentially aligned and each pair of such aligned openings 3 are positioned substantially midway of a pair of adjacent openings 2.

Disposed through the bore of the core member C is a predetermined number of telescopically assembled sleeves 4 of soft rubber or kindred elastic material. These sleeves 4 initially are of a length materially in excess of the length of the core member C so that after the sleeves 4 are inserted through the core member C, the opposite end portions of each of the sleeves 4 can be returned to overlie the outside of the core member C with the free extremities of the sleeve 4 vulcanized one to the other.

These sleeves 4 are loose with respect to the core member C so that said sleeves 4 and more particularly the innermost of said sleeves will have no adherence to the core member C but, on the contrary, the sleeves 4 will be free to have travel through the core member C after the fashion of an endless belt. This action is important as it facilitates the application of the appliance without injury to the organ.

Before the innermost sleeve 4 has its extremities united by vulcanization, the container as afforded by said innermost sleeve 4 is filled with fluid which readily circulates through the openings 2 and 3 of the core member C and such fluid is of a quantity to maintain the sleeves 4 expanded whereby is provided a cushion, particularly internally of the core member C, which directly engages the organ when the appliance is in use. The cushion engagement exerts sufficient pressure to provide an effective check for those having uncontrollable kidneys and also serves to create and maintain effective rigidity of the organ when conditions require to aid in treatment.

To facilitate the placing of the appliance, an elongated cap member M is provided which may be of rubber or other sufficiently flexible material and which member is adapted to be engaged over the outer end portion of the penis. Effective engagement of the cap member M is maintained by a surrounding retractile member 5 preferably a rubber band at the open end or face thereof. This band is of such size to assure requisite contrac-

tion at the receiving or open end of the cap member M.

Rigidly secured to the outer or closed extremity of the cap member M is an elongated flexible loop 6 of a length materially in excess of the length of the appliance proper and which loop, before application of the appliance, is threaded through the appliance which can be readily accomplished by forcing the same through the appliance by a digit of the hand. This threading can be effective either before or after the cap member has been applied.

After the appliance has been properly placed, which is at the lower part of the organ, the applied cap member M can be conveniently removed upon expansion of the retractile member or band 5.

From the foregoing description it is believed to be obvious that a therapeutic appliance constructed in accordance with my invention is particularly well adapted for use by reason of the convenience and facility with which it may be assembled and used, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A therapeutic appliance comprising a tubular core member open at both ends, a sleeve loosely threaded through the core member and having its opposite end portions returned to overlie the exterior of the core member, means for hermetically connecting the extremities of the sleeve, and a fluid filler within the sleeve.

2. A therapeutic appliance comprising a tubular core member open at both ends, a sleeve loosely threaded through the core member and having its opposite end portions returned to overlie the exterior of the core member, means for hermetically connecting the extremities of the sleeve, and a fluid filler within the sleeve, said sleeve being free to move through the core member.

3. A therapeutic appliance comprising a tubular core member open at both ends, a sleeve loosely threaded through the core member and having its opposite end portions returned to overlie the exterior of the core member, means for hermetically connecting the extremities of the sleeve, and a fluid filler within the sleeve, said sleeve being elastic.

4. A therapeutic appliance comprising a tubular core member open at both ends, a sleeve loosely threaded through the core member and

having its opposite end portions returned to overlie the exterior of the core member, means for hermetically connecting the extremities of the sleeve, said sleeve being free to move through the core member and said core member having its wall provided with openings.

5. A therapeutical appliance comprising a tubular core member open at both ends, a sleeve loosely threaded through the core member and having its opposite end portions returned to overlie the exterior of the core member, means for hermetically connecting the extremities of the sleeve, said sleeve being free to move through the core member and said core member having its wall provided with openings, said openings being arranged in series, the opening of each series being disposed lengthwise of the core member.

6. A therapeutical appliance comprising a tubular core member open at both ends, a sleeve loosely threaded through the core member and having its opposite end portions returned to overlie the exterior of the core member, means for hermetically connecting the extremities of the sleeves, said sleeves being free to move through the core member and said core member having its wall provided with openings, said openings being arranged in series, the opening of each series being disposed lengthwise of the core member, said series of openings being three in number, with two series substantially diametrically opposed and the third series substantially central of the said two series.

7. A therapeutical appliance comprising a tubular core member open at both ends, a sleeve loosely threaded through the core member and having its opposite end portions returned to overlie the exterior of the core member, means for hermetically connecting the extremities of the sleeves, said sleeves being free to move through the core member and said core member having its wall provided with openings, said openings being arranged in series, the opening of each series being disposed lengthwise of the core member, said series of openings being three in number, with two series substantially diametrically opposed and the third series substantially central of the said two series, the openings of the first two series being staggered with respect to the openings of the third series.

8. An appliance of the character set forth comprising, in combination, a tubular member the wall of which being compressible and an applicator including a cap member the open end of which being retractile, and an elongated flexible member for threading through the tubular member.

WILLIAM B. RUPE.
